[57] CLAIM

The design for a plastic bag forming and sealing apparatus, as shown.

DESCRIPTION

FIG. 1 is a top plan view of a plastic bag forming and sealing apparatus showing my new design;

FIG. 2 is a front elevational view of the apparatus;

FIG. 3 is a side elevational view of the apparatus, viewed from the right of FIG. 2;

FIG. 4 is a rear elevational view of the apparatus;

FIG. 5 is a side elevational view of the apparatus viewed from the left in FIG. 2; and

FIG. 6 is a bottom plan view of the apparatus.
